United States Patent Office

Des. 210,198
Patented Feb. 20, 1968

210,198

CABIN

Einar Svensson, 2248 NW. 190th Place,
Seattle, Wash. 98177

Continuation of design applications Ser. No. 83,043,
Dec. 15, 1964, and Ser. No. 4,124, Oct. 3, 1966.
This application Feb. 27, 1967, Ser. No. 6,472

Term of patent 14 years

(Cl. D13—1)

Fig. 6.

Fig. 7.

Fig. 8.

Fig. 9.

FIGURE 1 is a side-elevational view of a cabin showing my new design;

FIGURE 2 is a front-elevational view thereof;

FIGURE 3 is a sectional view thereof taken on line 3—3 of FIGURE 1;

FIGURE 4 is a rear view thereof;

FIGURE 5 is a side-elevational view of the cabin as viewed from the hidden side of FIGURE 1 and which cabin is presented on the slope of a hill;

FIGURE 6 is a side-elevational view of a modified form of the cabin shown in FIG. 1;

FIGURE 7 is a front elevational view thereof;

FIGURE 8 is a rear view of the cabin of FIGURE 6; and,

FIGURE 9 is a side-elevational view of the cabin as viewed from the hidden side of FIGURE 5, and which cabin is presented on the slope of a hill.

The supports shown in broken lines in the several views are disclosed for illustrative purposes only.

This application is a continuation of my copending applications, Ser. No. D. 83,043, filed Dec. 15, 1964, and D. 4,124, filed Oct. 3, 1966, and now abandoned.

I claim:

The ornamental design of a cabin, substantially as shown and described.
